UNITED STATES PATENT OFFICE

2,421,320

METHOD OF DESULPHURIZING
HYDROCARBON OILS

Joseph C. Ernest, Grand Rapids, Mich., assignor
to Mid-West Refineries, Inc., Grand Rapids,
Mich., a corporation of Michigan

Application August 25, 1945, Serial No. 612,668

3 Claims. (Cl. 196—28)

1

My invention relates to a method of desulphurizing hydrocarbon oils, and more particularly to a method of desulphurizing low boiling hydrocarbons in the vapor phase by contact with a solid adsorbent catalytic material of the clay type, while keeping the catalytic material in active condition by continuously subjecting it to the action of a menstruum.

In the catalytic desulphurization of hydrocarbon oils, a hydrocarbon oil is vaporized and passed in the vapor phase through a bed of catalytic material of the clay type such as fuller's earth, in which the sulphur compounds present in the hydrocarbon oil are converted to more easily removable sulphur compounds. During this process of desulphurization, certain side reactions occur, which have a tendency to render the catalyst surface inactive. When this occurs, the process is continued in another clay tower which is connected in parallel with the first clay tower to permit the first clay tower to be cleaned while the process is being conducted in the second clay tower. This represents an expenditure of time and material, as well as a capital investment in a plurality of clay towers.

One object of my invention is to provide a method of continuously desulphurizing hydrocarbon oils in vapor phase by contact with a solid adsorbent catalytic material of the clay type in which the clay bed is continuously kept in active condition by subjecting it to the action of a menstruum during the process.

Another object of my invention is to provide a process of continuously treating low boiling hydrocarbons such as motor fuels in the vapor phase to increase their octane number and lead susceptibility.

Another object of my invention is to provide a method of treating hydrocarbon oils boiling within the motor fuel range to improve their color.

Other and further objects of my invention will appear from the following description.

In general, my invention contemplates the heating of a hydrocarbon oil fraction boiling within the motor fuel range and the heating of a gas oil so that the motor fuel fractions will be in the vapor phase while the gas oil will be in the form of heavy vapors and then passing the motor fuel hydrocarbon vapors and gas oil hydrocarbon vapors through a bed of solid adsorbent catalytic material of the clay type. If desired the clay tower may be kept under an elevated pressure. In this manner the heavy hydrocarbons flush the catalyst bed and keep it active.

2

Some of the gas oil fractions may be in the liquid phase. I am not certain what occurs in the tower, but base my invention on the novel results achieved.

5 The accompanying drawing, which forms part of the instant specification, and which is to be read in conjunction therewith, shows a diagrammatic view of apparatus capable of carrying out the process of my invention.

More particularly, referring now to the drawing, motor fuel to be treated is withdrawn from tank 1 through pipe 2 controlled by valve 3 and pumped by pump 4 through pipe 5 through heat exchanger 6 through pipe 7 to any suitable heating means such as pipe still 8. The gasoline may be cracked gasoline or straight run gasoline or a mixture of these. Gas oil is stored in a tank 9 from which it is withdrawn through pipe 10 controlled by valve 11 and pumped by pump 12 into the pipe 5 joining the motor fuel being pumped from tank 1. The gas oil may be of any suitable gravity and boiling range, as for example a gravity of thirty-nine A. P. I., and may have an initial boiling point of say 400° Fahrenheit 15 and an end point in the neighborhood of 650° Fahrenheit. The pre-heated mixture of motor fuel and gas oil is heated first in convection heating coil 13 and then by radiant heat in coil 14 where the gasoline fractions are converted into vapors. Heat is supplied by burners 15, the flue gases being withdrawn through opening 16. If desired the gas oil may be heated in a separate still. For example, a second separate still 44 may be provided. In such case, valve 40 would be 20 closed and valves 41 and 48 would be open. The gas oil would then be pumped by pump 12 through pipe 42, through convection heating coil 43, through radiant heating coil 46, through pipe 47 into pipe 19 leading to the clay catalyst tower 17. Burner 45 is provided for heating the still 44. A clay tower 17 of any suitable design contains a bed of clay 18. The mixture of motor fuel vapors and gas oil vapors or heated liquid gas oil or all three passes into the tower 17 through pipe 19 and is adapted to be withdrawn through pipe 20, passing through the heat exchanger 6 and thence through pipe 21 to a fractionating tower 22. A valve 23 governs the pressure between the pumps and the fractionating tower and hence 25 the pressure in the clay tower 17. The oil and motor fuel is heated in the still 8 to a temperature in the vicinity of 600° Fahrenheit, and if desired under elevated pressure. By way of example and not by way of limitation, the pressure may be about fifty pounds per square inch.

The clay 18 may be of any suitable type. I have found that a clay obtained in the vicinity of Silvertown, Texas, is admirable for my purpose. It has the following approximate analysis:

	Per cent	5
SiO ₂ , silica (sand)	48 - 50	
Fe ₂ O ₃ , iron oxide	1 - 5	
Al ₂ O ₃ , aluminum oxide	13 - 14.5	
CaO, lime (calcium oxide)	11 - 12	10
MgO, magnesium oxide	.5 - 4	
SO ₃ , sulphur trioxide	3.5	
H ₂ O, water	4	

The vapors leave the fractionating tower through pipe 24 and are condensed in condenser 25. A cooling medium is supplied to the condenser through pipe 26 controlled by valve 27. A portion of the condensate is pumped through pipe 28 by pump 29 to control the top tower temperature. The condensate passes through pipe 30 to a receiver 31, from whence it is removed through pipe 32 controlled by valve 33 and passed to storage. Any gas which may be generated in the system may be withdrawn through pipe 34 controlled by valve 35. The heavy fractions containing dissolved sulphur are withdrawn from the bottom of the tower 22 through pipe 36 and pumped by pump 37 to a storage tank 38, from which they may be withdrawn through pipe 39 controlled by valve 40. If desired they may be pumped to the topped crude storage tank which feeds the cracking units.

Using a Michigan and West Texas crude in Dubbs cracking units, I have produced a cracked gasoline containing .25 per cent sulphur, and which was yellowish in color. Treating this cracked gasoline in accordance with my method with the Silverton clay described above, I have produced a gasoline containing .08 per cent sulphur, and which was water white in color. Surprisingly, however, I have found that gasoline thus treated increases in octane number and furthermore the lead susceptibility of the gasoline is greatly improved. By means of my method I am able to operate continuously with a single 45 tower. Where a plurality of towers are used I may run the towers continuously in parallel, thus increasing the output from a unit. The runs which can be made without changing clay are thus very greatly increased and it becomes un- 50 necessary to change the clay beds as frequently as would otherwise have to take place. Then, too, the activity of an ordinary clay bed progressively decreases. My method slows down the rate of decrease of activity to such an extent that 55 improved results are obtained to a remarkable degree.

It will be clear to those skilled in the art that many changes may be made in details without departing from the spirit of my invention. This is contemplated by and is within the scope of the appended claims. It is, therefore, to be understood that I am not to be limited to the particular details shown and described except within the ambit of the appended claims.

I claim:

1. In a process for desulphurizing hydrocarbons boiling within the motor fuel range in which motor fuel hydrocarbons are heated to vaporizing temperatures, the hydrocarbon vapors are passed through a bed of solid adsorbent catalytic material consisting essentially of clay whereby the sulphur compounds present in the hydrocarbon oil are converted into more easily removable sulphur compounds, the improvement comprising extending the catalytic activity of the catalyst bed by simultaneously heating a hydrocarbon oil boiling within the gas oil range to temperature substantially equal to that to which the motor fuel hydrocarbons are heated and introducing the heated gas oil into the catalytic bed as a menstruum to remove converted sulphur compounds tending to inactivate the catalyst, removing the motor fuel vapors and gas oil from the contacting catalytic zone, separating liquid hydrocarbons from hydrocarbon vapors and condensing the vapors to obtain a treated hydrocarbon condensate boiling within the motor fuel range.

2. A method as in claim 1 in which the temperature to which the motor fuel hydrocarbons are heated is in the vicinity of 650° F.

3. A method as in claim 1 in which the temperature to which motor fuel hydrocarbons are heated is in the vicinity of 650° F., and in which the heating and catalyst contacting zones are maintained under a super-atmospheric pressure in the vicinity of 50 pounds per square inch.
